FIG. 1.

Inventors
Ralph L. Hanscome
Ray Ferguson
By their Attorneys,

C. A. Snow & Co.

UNITED STATES PATENT OFFICE.

RALPH L. HANSOME AND RAY FERGUSON, OF KINGMAN, KANSAS.

SASH-HOLDER.

SPECIFICATION forming part of Letters Patent No. 470,396, dated March 8, 1892.

Application filed January 7, 1892. Serial No. 417,281. (No model.)

To all whom it may concern:

Be it known that we, RALPH L. HANSOME and RAY FERGUSON, citizens of the United States, residing at Kingman, in the county of Kingman and State of Kansas, have invented 5 a new and useful Sash-Holder, of which the following is a specification.

The invention relates to improvements in sash-holders for shutters, blinds, awnings, 10 and sliding doors.

The object of the present invention is to simplify and improve the construction of sash-holders and to increase their efficiency and ease of adjustment.

15 The invention consists in the construction and novel combination and arrangement of parts hereinafter fully described, illustrated in the accompanying drawings, and pointed out in the claim hereto appended.

20 In the drawings, Figure 1 is a sectional view of a portion of a window provided with a sash-holder constructed in accordance with this invention. Fig. 2 is a similar view taken at right angles to Fig. 1. Fig. 3 is a detail perspective view of the sash-holder.

25 Like numerals of reference indicate corresponding parts in all the figures of the drawings.

1 designates a casing constructed of suitable material and secured to a window-frame 30 2, and provided with an inner inclined face 3, adapted to force a roller 4 against a sash 5 to prevent the latter slipping downward and thereby hold the same at any desired adjustment. The roller 4 is journaled at the lower 35 end of a spring-actuated rod 6, which is mounted in the casing 1, and is adapted to be lifted by a lever 7 to raise the roller 4 out of engagement with the sash to permit the same

to be lowered or adjusted at any desired position. The rod 6 has its lower end bifurcated or forked to receive the roller 4, and the latter is held in engagement with the sash by a spiral spring 8, which is coiled around the rod and has its lower end engaging the 40 forked portion 9 of the rod and its upper end engaging a washer 10, which bears against the upper portion of the casing, and the latter is provided with an opening 11 to receive the rod. The lever 7 is pivoted by a pin 12 45 on a fulcrum-block 13, and it is arranged in a recess 14 thereof.

In order to prevent the edge of the sash which is engaged by the roller being injured, a metal strip 15 is secured to and set into the 50 sash.

It will be seen that the device is simple and inexpensive in construction and positive and reliable in operation.

What we claim is—

60 A sash-holder comprising a casing having an inclined inner face, a roller arranged in the casing and moving against the inclined face and adapted to engage a sash, a spring-actuated rod mounted in the casing and having the roller journaled on it, and a handle-lever fulcrumed intermediate its ends and having its inner end attached to the rod, substantially as described.

65 In testimony that we claim the foregoing as 70 our own we have hereto affixed our signatures in the presence of two witnesses.

RALPH L. HANSOME.
RAY FERGUSON.
